DENTAL COTTON ROLL HOLDER

Karl G. Von Grossmann, Minneapolis, Minn., assignor to Dental Products, Inc., Minneapolis, Minn.

Filed Aug. 24, 1970, Ser. No. 24,656

Term of patent 14 years

Int. Cl. D24—03

U.S. Cl. D24—1

FIG. 1 is a top plan view of a dental cotton roll holder showing my new design;

FIG. 2 is a side elevational view thereof; and

FIG. 3 is an end elevational view thereof; the bottom plan view, other side elevational view and other end elevational view are mirror images of FIGS. 1, 2 and 3 respectively.

I claim:

The ornamental design for a dental cotton roll holder, as shown and described.
